UNITED STATES PATENT OFFICE

WILLIAM L. GALVIN, OF CHICAGO, ILLINOIS

TWO-CYCLE INTERNAL-COMBUSTION ENGINE

Application filed May 17, 1928. Serial No. 278,384.

This invention relates to improvements in two-cycle internal combustion engines, and has for its principal object to provide a simple and effective means for scavenging the cylinder of burned gases and for producing increased suction during each power stroke.

My invention consists broadly in providing in combination with a reciprocating piston and cooperating crank shaft of the ordinary type, an auxiliary piston movable in timed relation with respect to said main piston so as to be substantially stationary during the early portion of the downward power stroke but to move rapidly toward said piston near the end of its power stroke and approach the same so as to effectively expel most of the exhaust gases from the cylinder, said auxiliary piston also having other actuating mechanism for raising the same in advance of the upward movement of the latter piston so as to cooperate therewith in proper suction and compression of the new charge in the cylinder.

As a preferred operating means for said auxiliary piston, I utilize two separate sets of cam actuating lever systems,—one for moving the piston downward during the power stroke, and the other for raising the piston during the suction and compression stroke, as will hereinafter more fully appear.

The invention may best be understood by reference to the accompanying drawings, in which

Figure 1 is a diagrammatic side view of a motor showing a relative arrangement of the cylinder, main and auxiliary pistons and the lever systems for actuating said auxiliary piston.

Figure 2 is a side view of the motor shown in Figure 1, showing the general arrangement of the two sets of lever systems and their connection with the single auxiliary piston.

Figures 3, 4 and 5 are diagrammatic views showing the operation of the exhaust levers during the power or downward stroke of the main piston.

Figures 6, 7 and 8 are views similar to Figures 3, 4 and 5 but showing the operation of the inlet levers during the suction and compression stroke.

Figure 9 is a diagram showing the relative positions of the main and auxiliary pistons throughout one cycle of operation as determined by one revolution of the crank shaft.

Referring to details of the drawings, my motor includes a cylinder 10 having a main piston 11 reciprocably movable therein and connected by a piston rod 12 to a crank pin 13 of crank shaft 14 in the usual manner. An inlet port 15 is provided at a point just above the lower limit of movement of the main piston 11. An exhaust port 16 is also provided, preferably opposite and slightly above the inlet port, and provided with a check valve 16^a of any well known form, as shown. Suitable ignition means including a spark plug (not shown) or its equivalent, is provided at a suitable point 17 adjacent the upper end of the cylinder. The cylinder 10 is mounted on a crank case 18.

Referring now more particularly to the novel features of my invention, I provide an auxiliary piston 20 herein of the same diameter as the main piston, and fitting within the upper end of cylinder 10 so as to form a movable head thereof.

The auxiliary piston is moved through two sets of lever systems which are alternately actuated by two cams 25 and 26, rotatable in timed relation with the crank shaft 14. In the preferred form shown, these two cams are both mounted on a single cam shaft 27 suitably driven from the crank shaft 14 as through an idler gear 28, the arrangement being such that said cam shaft revolves at the same speed as the crank shaft 14.

One of the sets of levers actuated by the cam 25 is operative immediately following the power stroke for exhausting the burned gases. These levers and their actuating cam will hereinafter be referred to as the "exhaust" levers, and "exhaust" cam, respectively. As shown herein, the exhaust levers include a bell crank lever 30 having one end thereof provided with a roller 31 adapted for engagement with the exhaust cam 25 and the other end connected through a link 32 to a second bell crank lever 33. The two bell crank levers are respectively fixed upon pivot pins 30^a and 33^a. The inner end of the bell

crank lever 33 is connected through link 34 to an intermediate point of lever arm 35, constituting a lever of the third class, fixed at one end on a pivot pin 35^a and at the other end to a link 36 connected to a push rod 37. Said push rod extends through a suitable bearing 38 supported in the upper end of the crank case 18.

The upper end of the push rod 37 is connected through a link 39 to one arm 40^a of a yoked rocking lever 40 which is arched upwardly over the cylinder 10 and is pivoted on a bracket 10^a. Said rocking lever is connected at its upper end to the auxiliary piston 20 through the pivoted link 41. The arrangement of the exhaust levers and actuating cam is such as to provide a very rapid downward movement of the auxiliary piston at a speed approximating four-to-one over the speed of the main piston during a certain period of downward movement of the latter, as will hereinafter more fully appear.

Referring now to the system of levers and their actuating cam 26, hereinafter referred to as the "intake" levers and "intake" cam, respectively, the same consists of a system somewhat similar to that of the exhaust levers but arranged for moving the auxiliary piston upwardly and at a somewhat lower rate of speed than that caused by the exhaust levers and cam. The intake levers include a bell crank lever 42 having one end thereof provided with a roller 43 for engagement with the intake cam 26 and having its other end connected through a link 44 to a bell crank lever 45. The two bell crank levers 42 and 45 are pivotally mounted respectively on fixed pins 42^a and 45^a. The inner end of the bell crank lever 45 is connected by link 46 to an intermediate point of lever 47 which lever constitutes a lever of the third class, being pivotally mounted at one end on a fixed pivot pin 47^a and at the other end connected through link 48 to a push rod 49. Said push rod extends upwardly through suitable bearing 49^a in the top of crank case 18 and is connected to another arm 40^b of rocking member 40 by means of a link 49^b.

The operation of the engine above described is best shown in Figures 3 to 8, taken in connection with the motion diagram in Figure 9. In the latter diagram, the upper heavy line 20 represents the movement of the auxiliary piston 20, the lower line 11 represents the relative movement of the main piston, and the corresponding angular movement of the crank shaft is indicated at the several points of one revolution by the several vertical lines marked 0°, 45°, 90°, etc., from the initial point of each cycle.

Referring now to the description of one cycle of operation, Figure 3 indicates the relative position of the parts when the main piston has just passed dead center, with the crank shaft rotating in a clockwise direction,

and in which the charge within the cylinder has been ignited so as to start the piston downward on its power stroke. As will be seen from Figure 3, the exhaust cam 25 is rotating in a clockwise direction but has not yet reached a position to move the exhaust levers and through the latter to move the auxiliary piston. Accordingly, the auxiliary piston is maintained in a stationary position until the crank shaft has moved through an arc of nearly 90° as shown in Figure 4, when the exhaust port 16 is beginning to open, at which point the exhaust cam begins to actuate its lever system and move the auxiliary piston downwardly, as shown in Figure 4. From inspection of the diagram of Figure 9, it will be seen that this downward movement of the auxiliary piston is extremely rapid, (being about four times as fast as the main piston) so that a full stroke of the auxiliary piston is completed within a range of approximately 25°, that is to say, between about 90° and 115° of rotation of the crank shaft and before the main piston begins to open the inlet valve. At the bottom of the auxiliary piston's stroke its lower surface almost meets the upper surface of the main piston at a point opposite the exhaust port, so as to force practically all of the burned gases from the cylinder through the exhaust port, as will be understood from the diagram, and as also shown in Figure 5.

At this point the exhaust stage is completed, and the exhaust cam rotates out of engagement with its lever system.

Immediately thereafter, the inlet cam 26 comes into operative engagement with the inlet levers, as indicated in Figure 6. The inlet levers are then actuated to raise the auxiliary piston while the main piston continues its downward movement, but the arrangement of the inlet levers is such as to cause somewhat slower upward movement of said auxiliary piston (about 2 to 1 relative to the main piston) than is its downward movement. As a result of said upward movement of the auxiliary piston, it will be seen from Figure 9 that the two pistons are moving away from each other until the main piston reaches the lowermost limit of its stroke, and during this period the main piston has passed below the upper edge of the inlet port so as to open the same. The rapid separation of the two pistons therefore produces a suction stroke for intake of a fresh charge between the points represented by lines 115° and 245° on the diagram in Figure 9. As will also be seen from this diagram, the two pistons are not quite at maximum point of separation from each other when the main piston reaches its lowermost position of 180°, but the suction stage continues beyond this point, due to the more rapid upward movement of the auxiliary piston, until the main piston closes the intake port in its upward movement, and the auxiliary piston completes its upward

movement, as shown in Figure 7, this being at about 245° of rotation of the crank shaft.

After the intake port has been closed, the main piston continues to move upwardly to compress the charge, although it will also be observed that substantial compression is not commenced until the auxiliary piston is returned to its uppermost position, as shown in Figure 7. When the main piston has reached its uppermost position of full compression, as shown in Figure 8, the inlet levers and cam pass out of engagement with each other so as to permit the exhaust cam and lever to become operative during the next

15 succeeding cycle.

Referring now more particularly to the advantages of a two-cycle engine as above described, it will be observed, first, that the full effect of combustion of the power stroke 20 is effective upon the main piston but approximately all burned gases are expelled from the cylinder as soon as the exhaust port is open. Second: A new charge is drawn into the cylinder by cooperation of the auxiliary and 25 main pistons to form a suction stroke, said charge being relatively large and therefore capable of producing a high compression. From a structural standpoint also, my improved motor has the advantages of utilizing 30 a simple form of cam and compound, speed-increasing levers for operating the auxiliary piston instead of a more complicated system of mechanical valves, and I find that the lever systems shown are more compact and positive in operation than is possible with cam 35 devices which might be devised to give equal relative movements of the auxiliary piston.

While I have illustrated and described the particular embodiment of my invention, it 40 will be understood that I do not wish to be limited to the exact construction shown and described but that various changes and modifications may be made without departing from the spirit and scope of my invention.

45 I claim as my invention:

1. In a two-cycle internal combustion engine, a cylinder, a power piston and an auxiliary piston both reciprocably movable in said cylinder, an inlet port adjacent the lower 50 limit of movement of said power piston, an exhaust port above said inlet port, and means in timed relation with said power piston for moving said auxiliary piston downwardly after the explosion so as to approach the power piston and 55 expel the burned gases through said exhaust port during an intermediate portion of the downward stroke of said power piston, and means for moving said auxiliary piston upwardly during the final 60 portion of the downward stroke of said power piston whereby both of said pistons cooperate in producing suction for intake of gases through said intake port, said means for moving said auxiliary piston downwardly and upwardly in timed relation with said main pis-

ton comprising two independently actuated successively operable compound lever systems.

2. In a two-cycle internal combustion engine, a cylinder, a power piston and an auxiliary piston both reciprocably movable in said cylinder, an inlet port adjacent the lower limit of movement of said power piston, an exhaust port above said inlet port, a compound lever system actuated in timed relation with said power piston for moving said auxiliary piston downwardly after the explosion so as to approach the power piston and expel the burned gases through said exhaust port during an intermediate portion of the 70 downward stroke of said power piston, and a second compound lever system for moving said auxiliary piston upwardly during the final portion of the downward stroke of said power piston whereby both of said pistons 75 cooperate in producing suction for intake of gases through said intake port, said lever systems having independent cam actuating means therefor.

3. In a two-cycle internal combustion engine, a cylinder, a power piston and an auxiliary piston both reciprocably movable in said cylinder, an inlet port adjacent the lower limit of movement of said power piston, an exhaust port above said inlet port, a compound lever system actuated in timed relation with said power piston for moving said auxiliary piston downwardly after the explosion so as to approach the power piston and expel the burned gases through said exhaust 90 port during an intermediate portion of the downward stroke of said power piston, and a second compound lever system for moving said auxiliary piston upwardly during the final portion of the downward stroke of said power piston whereby both of said pistons 95 cooperate in producing suction for intake of gases through said intake port, said lever systems having independent cam actuating means therefor. 100

4. In a two-cycle internal combustion engine, a cylinder, a power piston and an auxiliary piston both reciprocably movable in said cylinder, an inlet port adjacent the lower limit of movement of said power piston, an exhaust port above said inlet port, a compound lever system actuated in timed relation with said power piston for moving said auxiliary piston downwardly after the explosion so as to approach the power piston and expel the burned gases through said exhaust 110 port during an intermediate portion of the downward stroke of said power piston, and a second compound lever system for moving said auxiliary piston upwardly during the final portion of the downward stroke of said power piston whereby both of said pistons 115 cooperate in producing suction for intake of gases through said intake port, said lever systems having independent cam actuating means therefor, and the first lever system 120 moving said auxiliary piston downwardly at approximately four times the speed of said power piston.

4. In a two-cycle internal combustion engine, a cylinder, a power piston and an auxiliary piston both reciprocably movable in said cylinder, an inlet port adjacent the lower limit of movement of said power piston, an exhaust port above said inlet port, a compound lever system actuated in timed relation with said power piston for moving said auxiliary piston downwardly after the explosion so as to approach the power piston and expel the burned gases through said exhaust port during an intermediate portion of the downward stroke of said power piston, and a second compound lever system for moving said auxiliary piston upwardly during the final portion of the downward stroke of said power piston whereby both of said pistons 125 cooperate in producing suction for intake of gases through said intake port, said lever systems having independent cam actuating means therefor. 130

tons cooperate in producing suction for intake of gases through said intake port, said lever systems having independent cam actuating means therefor, and said first lever system moving said auxiliary piston downwardly at approximately twice the speed of upward movement produced by said second lever system.

5. In a two-cycle internal combustion engine, a cylinder, a power piston and an auxiliary piston both reciprocably movable in said cylinder, an inlet port adjacent the lower limit of movement of said power piston, an exhaust port above said inlet port, a compound lever system actuated in timed relation with said power piston for moving said auxiliary piston downwardly after the explosion so as to approach the power piston and expel the burned gases through said exhaust port during an intermediate portion of the downward stroke of said power piston, and a second compound lever system for moving said auxiliary piston upwardly during the final portion of the downward stroke of said power piston whereby both of said pistons cooperate in producing suction for intake of gases through said intake port, said lever systems having independent cam actuating means therefor, and the first lever system moving said auxiliary piston downwardly at approximately four times the speed of said power piston, and said second lever system moving said auxiliary piston upwardly at approximately one half the speed of downward movement produced by said first lever system.

Signed at Chicago, Ill., this 12th day of May, 1928.

WILLIAM L. GALVIN.
